UNITED STATES PATENT OFFICE.

HEBER C. PETERS, OF NEW YORK, N. Y., ASSIGNOR TO BURROUGHS ADDING MACHINE COMPANY, OF DETROIT, MICHIGAN, A CORPORATION OF MICHIGAN.

ADDING-MACHINE.

1,094,468.

Specification of Letters Patent.

Patented Apr. 28, 1914.

Original application filed August 22, 1904, Serial No. 221,655. Divided and this application filed February 16, 1909, Serial No. 478,295.

To all whom it may concern:

Be it known that I, HEBER C. PETERS, a citizen of the United States, residing at New York, in the county of New York and State 5 of New York, have invented certain new and useful Improvements in Adding-Machines, of which the following is a specification.

This application is a division of my application filed August 22, 1904, Serial No. 221,655.

The invention relates to means for subdividing the printing section of an adding machine by suspending co-operative action 15 between elements of the impression devices, so that two or more columns of imprints can be made in one series of operations of the machine. In machines of the Burroughs type (see Burroughs Patents 505,963 and 20 505,078, issued September 12, 1893,) printing hammers are employed corresponding in number with the number of rows of amount keys and these hammers are controlled by latches adapted to be individually displaced 25 by reason of depression of amount keys followed by an operation of the machine and such latches are further adapted to successively displace each other to provide for the filling in of ciphers where no digits occur 30 in the amount to be recorded.

The present invention relates more particularly to the coupling together of adjacent latches or like elements of the printing mechanism so as to provide for uncoupling 35 whenever it is desired to suspend the successive displacement or tripping of latches for double column work.

It may further be said that the invention relates to a species characterized by a coupling device which is carried on or by one 40 of an adjacent pair of latches or like elements and adapted to be moved into and out of engagement with the other latch of such pair.

45 In the drawings which accompany and form part of this specification Figure 1 represents in left side elevation a machine of the Burroughs type equipped with a form of means for embodying the present invention; Fig. 2 shows the printing section in left side elevation on an enlarged scale as compared with Fig. 1, certain cross rods and shafts of the machine appearing in sec-

tion and moving parts as when latches are disconnected; Fig. 3 is a similar view showing such latches connected; Fig. 4 is a cross-sectional detail on line 4--4 of Fig. 3; Fig. 5 a horizontal section on line 5--5 of Fig. 2; and Figs. 6 and 7 detail perspectives.

The adding machine in general is so familiar as to require no extensive description and reference may be had to the before-mentioned prior patents for the details of construction not herein mentioned. The present description will be confined to the printing section of the machine which comprises the usual pivoted hammers 715 adapted to percussively strike the type plates 618, the latter being as usual mounted in segmental series upon the rear ends of levers 611. The numeral 716 designates the usual hammer driving levers impelled by springs 780. The numeral 717 designates latches or detents of the usual form which normally restrain the hammer-driving levers and the hammers, such latches having laterally-turned tails d' overlying shoulders d^2 on adjacent latches. For the purposes of the present invention a special latch 717^b is employed at a selected location. The particular construction of such latch which makes it different from the regular latches will be hereinafter pointed out. Pawls 718 are mounted as usual upon a cross rod 704 of a swinging bail and the springs 780 connect these pawls with the hammer-driving levers so that said springs besides constituting the means for impelling the hammers also enforce engagement between the pawls and the latches. The before-mentioned bail swings 85 forward and back in each operation of the machine and in any banks where amount keys 231 have been depressed the pawls will act as usual to disengage the latches from the hammer drivers. In other banks the up-turned tails of the pawls engage cam surfaces or edges of the levers 611 so as to cause the pawls to escape the latches. The laterally-turned tails d' , however, will cause 90 successive displacement of latches notwithstanding such displacement of the pawls.

In carrying out the present invention in the form here shown the special latch 717^b does not have a laterally-turned tail but a slotted forward portion 717^a with a ledge or flange 717^c on the left-hand side below the

slot as shown in Figs. 2 to 7, the next adjacent latch 717 on the left, as the parts are viewed from the front of the machine, having its tail d' overlying this ledge or flange 5 so as to operate upon it with the same effect that others of the tails d' act upon portions d^2 of adjacent latches. A coupler or contact device in the form of a slide piece is carried by said latch 717^b, being composed of plates 10 717^e on opposite sides of the forward portion 717^a of said latch, said plates connected by studs or rivets 717^c which extend through the slot of said latch. The forward one of these studs is elongated as shown in Figs. 4, 15 5 and 7 so as to be capable of overlying the shoulder d^2 of the adjacent latch to the right but the movement which the slide piece may have by reason of its slot-and-pin connection with the latch is sufficient to provide for said 20 stud occupying a position forwardly beyond such shoulder as shown in Fig. 5, and a spring 717^d of bow-form secured at one end in the latch 717^b and at the other end engaged with the slide piece, acts to thrust the 25 latter forwardly to so position said stud as represented in Figs. 2 and 5. With the stud so positioned the latch 717^b when displaced will not affect the adjacent latch to the right and the cipher printing operation will be interrupted. The slide piece has another stud 30 717^f at its forward end which overlies a curving edge of one arm of a lever 790^a, the latter pivoted upon a suitable cross shaft and having an upper arm carrying a stud e 35 engaged with the bifurcated end of an arm 792^a which is secured to a rock shaft 793. The latter extends to the left side of the machine and carries another arm 296 secured to it and extending forwardly and pivotally 40 connected to the lower end of a key stem 297. The latter slides through the top plates 212, 213 of the machine and is notched as at f to provide for catching under the upper one of said plates which locks it in depressed position. A spring 298 normally upholds the 45 key stem as shown in Fig. 1, such spring being superior to the previously mentioned spring 717^d. It will be seen that by reason of said spring 298 normally upholding the 50 key 297 the arm 296 will be normally upheld and the arm 792^a normally depressed to the position shown in Fig. 3 so that the lower arm of the lever 790^a is normally held rearward and upward as also shown in Fig. 3. 55 By reason of the engagement of said latter arm with the stud 717^f the slide piece 717^e will be normally held rearward with its stud 717^c overlying the shoulder d^2 of the adjacent latch to the right. Consequently, the 60 usual successive tripping of latches can take place throughout the series. However, depression of the key 297 will rock the lever 790^a to the position shown in Fig. 2, whereupon the spring 717^d acts upon the slide 65 piece to take the stud 717^c from over the

shoulder d^2 . This will obviously effect suspension of the successive tripping of latches or in other words establish the so-called "split."

The construction above described is susceptible of modification within the scope of the invention and so the claims which follow vary considerably in scope.

What I claim is:

1. In a machine of the character described, the combination of spring-actuated printing hammers, restraining latches, and a movable coupler carried by one latch and adapted to engage the adjacent latch.

2. The combination with the hammers and actuating means and movable detents of a recording mechanism, of a contact device on one detent movable into and out of position to engage the next detent.

3. In a machine of the character described, the combination of spring-actuated printing hammers, restraining latches, and a coupler movably mounted on one latch and adapted to operatively engage a neighboring latch.

4. In a machine of the character described, the combination of spring-actuated printing hammers, restraining latches, a movable coupler carried by one latch and normally engaging a neighboring latch, and means for moving the coupler to disengage it from such neighboring latch.

5. In a machine of the character described, the combination of spring-actuated printing hammers, restraining latches, and a coupler movably mounted on one latch and spring drawn into engagement with a neighboring latch.

6. In a machine of the character described, the combination of spring-actuated printing hammers, restraining latches, a coupler movably mounted on one latch and spring drawn into engagement with a neighboring latch, and means for moving it out of such engagement.

7. In a machine of the character described, the combination of spring-actuated printing hammers, restraining latches, a coupler movably mounted on one latch and adapted to operatively engage a neighboring latch, a spring tending to move said coupler out of engagement with the neighboring latch, and means for holding the coupler engaged therewith.

8. In a machine of the character described, the combination of spring-actuated printing hammers, restraining latches, a coupler movably mounted on one latch and adapted to operatively engage a neighboring latch, a spring tending to move said coupler out of engagement with the neighboring latch, and means for holding the coupler engaged therewith including a superior spring and a key.

9. In a machine of the character described, the combination of spring-actuated printing hammers, restraining latches, and a coupler

- slidably mounted on one latch and adapted to operatively engage a neighboring latch.
10. In a machine of the character described, the combination of spring-actuated printing hammers, restraining latches, and a slide piece carried by one latch and having a laterally projecting stud to act upon the neighboring latch.
11. In a machine of the character described, the combination of spring-actuated printing hammers, restraining latches, a slide piece carried by one latch and having a laterally projecting stud to act upon the neighboring latch, a spring thrusting the slide piece in a direction to disengage it from such neighboring latch, and means for holding the latch engaged therewith.
12. In a machine of the character described, the combination of spring-actuated printing hammers, restraining latches, a slide piece carried by one latch and having a laterally projecting stud to act upon the neighboring latch, a spring thrusting the slide piece in a direction to disengage it from such neighboring latch, and means for holding the latch engaged therewith comprising a superior spring and a key.
13. In a machine of the character described, the combination of spring-actuated printing hammers, restraining latches, and a slide piece carried by one latch and having a laterally projecting stud to act upon the neighboring latch, and a stud by which to operate it, together with means applied to said latter stud for shifting the slide piece.
14. In a machine of the character described, the combination of spring-actuated printing hammers, restraining latches, and a slide piece carried by one latch and having a laterally projecting stud to act upon the neighboring latch, and a stud by which to operate it, together with a lever engaging said latter stud for shifting the slide piece.
15. In a machine of the character described, the combination of spring-driven hammers, restraining latches, and a coupler movably mounted on one latch and having a stud to engage a neighboring latch.
16. In a machine of the character described, the combination of spring-driven hammers, restraining latches, and a coupler movably mounted on one latch and having a stud to engage a neighboring latch and a stud by which to operate it.
17. In a machine of the character described, the combination of spring-driven hammers, restraining latches, and a coupler movably mounted on one latch and having a stud to engage a neighboring latch and a stud by which to operate it together with means applied to said latter stud for shifting the coupler.
18. In a machine of the character described, the combination of spring-driven hammers, restraining latches, and a coupler movably mounted on one latch and having a stud to engage a neighboring latch and a stud by which to operate it together with means applied to said latter stud for shifting the coupler.
19. In a machine of the character described, the combination of spring-driven hammers, restraining latches, and a coupler movably mounted on one latch and yieldingly held in engagement with a neighboring latch.
20. In a machine of the character described, the combination of spring-driven hammers, restraining latches, and a coupler movably mounted on one latch and yieldingly held in engagement with a neighboring latch, and means for disengaging it therefrom.
21. In a machine of the character described, the combination of spring-driven hammers, restraining latches, and a coupler movably mounted on one latch and yieldingly held in engagement with a neighboring latch, and means for disengaging it therefrom including a depressible key.
22. In a machine of the character described, the combination of spring-driven hammers, restraining latches, and a coupler movably mounted on one latch and yieldingly held in engagement with a neighboring latch, and means for disengaging it therefrom including a depressible key, and a lever operated thereby.
23. In a machine of the character described, the combination of spring-driven hammers, restraining latches, and a coupler slidably mounted on one latch and yieldingly held in engagement with a neighboring latch.
24. In a machine of the character described, the combination of spring-driven hammers, restraining latches, and a coupler slidably mounted on one latch and yieldingly held in engagement with a neighboring latch, and means for disengaging it therefrom.
25. In a machine of the character described, the combination of spring-driven hammers, restraining latches, and a coupler slidably mounted on one latch and yieldingly held in engagement with a neighboring latch, and means for disengaging it therefrom including a depressible key.
26. In a machine of the character described, the combination of spring-driven hammers, restraining latches, and a coupler slidably mounted on one latch and yieldingly held in engagement with a neighboring latch, and means for disengaging it therefrom including a depressible key and a lever operated thereby.
27. In a multiple-order adding machine, in combination, adding mechanism, printing mechanism including the multiple spring actuated type-hammers, automatic

cipher-printing mechanism, a pivoted member for coupling together and uncoupling the hammer-release mechanism in two adjacent orders, and an optionally operable member for actuating said pivoted member.

28. In a machine of the character described, the combination of printing hammer releasing devices, a movable coupler mounted upon one of the latter to couple the same to and uncouple it from the neighboring device, and manipulative means loosely engaged with said coupler for shifting the same.

29. In a machine of the character described, the combination of printing hammer releasing devices, a movable coupler mounted upon one of the latter to couple the same to and uncouple it from the neighboring device, and a pivoted member loosely engaging said coupler to shift the same.

30. In a machine of the character described, the combination of printing hammer releasing devices, a movable coupler mounted upon one of the latter to couple the same to and uncouple it from the neighboring device, a pivoted member loosely engaging said coupler to shift the same, and a manipulative device engaging said pivoted member.

31. In a machine of the character described, the combination of printing hammers, releasing devices therefor, and a coupler wholly supported by one such device and slideable thereon into and out of position to coöperate with the adjacent device.

32. In a machine of the character described, the combination of printing hammers, releasing devices therefor, a coupler wholly supported by one such device and slideable thereon into and out of position to coöperate with the adjacent device, and a

spring for moving said coupler to one of its two positions.

33. In a machine of the character described, the combination of printing hammers, releasing devices therefor, a coupler wholly supported by one such device and slideable thereon into and out of position to coöperate with the adjacent device, and a key and connections for controlling said coupler.

34. In a machine of the character described, the combination of printing hammers, releasing devices therefor, and a coupler slideable upon one such device in the general plane thereof into and out of position to coöperate with the adjacent device.

35. In a machine of the character described, the combination of printing hammers, releasing devices therefor, a coupler slideable upon one such device in the general plane thereof into and out of position to coöperate with the adjacent device, and a key and connections for operating said coupler.

36. In a machine of the character described, the combination of printing hammers, releasing devices therefor, a coupler slideable upon one such device in the general plane thereof into and out of position to coöperate with the adjacent device, and a spring-held key and connections for operating said coupler.

37. In a machine of the character described, the combination of printing hammers, releasing devices therefor, and a coupler wholly supported by one such device and movable thereon into and out of position to coöperate with the adjacent device.

HEBER C. PETERS.
